UNITED STATES PATENT OFFICE.

THOMAS H. HOLLIS, OF PITTSBURGH, PENNSYLVANIA.

WATER-DISTRIBUTING SYSTEM.

1,358,741.

Specification of Letters Patent. Patented Nov. 16, 1920.

Application filed May 5, 1917. Serial No. 166,510.

To all whom it may concern:

Be it known that I, THOMAS H. HOLLIS, a citizen of the United States, residing at Pittsburgh, in the county of Allegheny and 5 State of Pennsylvania, have invented certain new and useful Improvements in Water-Distributing Systems, of which the following is a specification.

My invention relates to water distributing systems and particularly those employing what are known as jet pumps. It has for its primary objects; the simplification and improvement of the system covered by my Patent No. 1,059,609, issued April 22, 15 1913; the provision of a system wherein the distributing tank may be reduced to a minimum size and fresh water secured at any time direct from the well and independent of the distributing tank; and the provision 20 of an improved arrangement of the pump which is preferably divided into two pumping elements instead of employing the single pump of the patent. Certain embodiments 25 of the invention are illustrated in the accompanying drawings, wherein—

Figure 1 is a diagrammatic perspective view showing the general arrangement of the parts; Figs. 2 and 3 are enlarged detail views of certain of the parts of the system 30 shown in Fig. 1; and Figs. 4 and 5 are diagrammatic views of modified arrangements.

Briefly stated, the system in its preferred form includes two rotary pump elements driven from a motor in connection with a 35 jet pump placed in the well and apparatus for securing an automatic control of the operation of the motor. A distributing tank is employed in which air pressure is automatically accumulated so that the system is 40 always under the desired amount of pressure, but such distributing tank is made relatively small and out of the line of flow through the distributing pipes, so that water fresh from the well can be secured, 45 without such water passing through the distributing tank. The arrangement is also preferably such that the opening of an outlet faucet starts the operation of the motor and pumping mechanism, while the closing 50 of the outlet cuts off the power to the motor.

Referring first to the general arrangement, A is the jet pump located in the well B, C is an electric motor for driving the rotary pump elements or members D and E; 55 F is the distributing pipe leading from the

pumping mechanism; and G is the distributing tank provided with the controlling mechanism for automatically cutting off or turning on the electric current to the motor C.

The jet pump may be of any approved type, such for instance, as shown in my patent referred to, said pump being provided with a pipe 1 for supplying water to give the lifting effect, and the relatively larger pipe 2 through which the water is lifted and which constitutes the outlet of the jet pump. The pump comprises a pair of rotary pumping members or elements D and E, which for convenience may be referred to, respectively, as "low" and "high" pressure elements or members, since the pump D normally operates against a lower pressure than the pump E. These pumps may be of any desired type and have their rotating 70 elements carried upon the shaft 3 of the electric motor C.

Water is supplied to the pipe 1 from the high pressure pump E, the volume of water delivered through this pipe being approximately one-half that delivered by the up-flow pipe 2. The pipe 2 constitutes the inlet to the low pressure pump D, such pump D discharging through the distributing pipe F leading to the various faucets or taps 4 and 5, and through the pipe 6 which constitutes the inlet of the high pressure pump E. Under ordinary conditions, therefore, about one-half of the water from the pump D passes through the distributing pipe F 80 for use while the other half passes back to the pump E which operates the jet pump, such proportions, however, being only approximate as the question of proportions is a matter of design and depends upon the 85 conditions to be met.

Connected with the distributing pipe F by means of the pipe 7 is the distributing tank G which may be made relatively small and inexpensive since its primary function is 100 merely to keep the system under pressure until the pump is fully started and to serve as a regulating means for governing the starting and stopping of the pumping mechanism. In order that the tank may be supplied with air under pressure the pipe 7 has therein an inspirator 8 as shown in Fig. 3, such inspirator being similar to that set forth in my patent heretofore referred to. The water passing through the reduced por- 110

tion 9 sucks in air through the lateral opening 10, and when the pressure of the air in the tank reaches a certain predetermined amount the ball check valve 11 prevents any 5 outflow of water through the passage 10, and also prevents such outflow when no water is flowing through the inspirator. By means of this device sufficient air pressure is 10 accumulated and maintained in the system to provide the necessary pressure before the pump starts. Located in the tank is a controlling mechanism and switch whereby the current to the motor is cut off when the water reaches a predetermined height and 15 whereby the current is turned on when the water drops below a certain height in the tank. As a matter of fact the capacity of the tank is preferably so small that the switch is operated to throw in the current 20 almost as soon as an outlet from the system is opened, and to break the circuit very quickly after the outlet is closed. Extending inward from the wall of the tank (Fig. 2) is a corrugated diaphragm 12 having its 25 inner end 13 closed and carrying the conical member 14 so that such conical member is moved endwise by the movement of the end 13 of the diaphragm. The end 13 is moved in and out by means of the float 15, 30 such float being carried upon a bell crank lever 16 pivoted at 17 to the bracket 18. The short end of the lever is connected to the center of the end 13 by means of the link 19. The switch is preferably of the snap order 35 and includes a spiral spring 20 encircling the cone-shaped member 14 and connected to a collar 21 so that the collar moves endwise of the member 14 with the spring. 22 and 40 23 are a pair of contacts connected with the wires 24 and 25 constituting a part of the motor circuit as diagrammatically shown in the drawing. When the water in the tank drops below a certain point the float moves down causing the end of the diaphragm 13 45 and the member 14 carried thereby to move to the right. After the member 14 is moved so that its central portion is to the right of the spring 20, such spring suddenly moves the collar 21 to the left engaging the contacts 22 and 23 and completing the circuit. When the water rises above a predetermined height in the tank the float causes a 50 reverse movement of the member 14 and a consequent breaking of the circuit. 55 In operating the system the opening of one of the faucets 4 or 5 permits a flow of water due to the pressure accumulated in the tank G. Such flow of water immediately lowers the level in the tank G and causes the 60 switch to operate as heretofore set forth completing the motor circuit and starting the pumping elements. The inlet to the jet pump is preferably provided with a ball check valve *a* so that the pipes 1 and 2 are 65 constantly full of water, keeping the sys-

tem primed. The starting of the motor, therefore, starts the operation of the rotary pumps E and D, the pump E forcing water down through the pipe 1 and causing an upflow through the pipe 2 while the pump 70 D operates to distribute the water thus raised, a part of the water passing through the distributing pipe F and another part through the pipe 6 to the inlet side of the high pressure pump E. 75

This operation ordinarily continues as soon as the outlet from the system is opened, since the pressure in the tank G tends to prevent it from filling up and raising the float until the outlet is closed. As soon as 80 the outlet is closed, however, the continued operation of the pump causes a flow of water up through the pipe 7 to the tank G and the float is raised operating the switch and breaking the circuit to the motor. The 85 flow of water through the pipe 7 sucks in air through the inspirator 8 so that a proper proportion of air is always maintained in the tank and the necessary pressure in the system is secured. 90

Fig. 4 illustrates in diagrammatic form a modification involving a single pump 36 instead of the two pumps of Fig. 1. In this construction 1 is the pipe leading up from the jet pump A, and 2 and F constitute the 95 outlet pipes from the pump 36. The pipe 2 leads down into the well to operate the jet pump A while the pipe F constitutes the distributing outlet connected to the distributing tank G by means of the pipe 7 100 carrying the inspirator 8, such parts corresponding to similar parts in Fig. 1, and the operation of the motor driving the pump 36 being the same as in the construction heretofore described. In this construction 105 with a single pump a back pressure means is necessary in the pipe F in order that sufficient pressure may be accumulated in the pipe 2 to operate the jet pump A, and this back pressure may be provided by placing 110 a resistance means 44 in the pipe F, which resistance means may be a valve yieldingly resisting the flow of water through the pipe or a reduction in the diameter of the pipe to throttle the flow. This is not as desirable 115 an arrangement as the one constituting the preferred embodiment of the invention heretofore described, but is illustrated to indicate the scope of the invention and the variety of arrangements possible. The construction has one of the advantages incident to that of the construction of Fig. 1 as compared to that of the patent, namely, that the distributing tank G is placed out of the line of flow and may be made relatively small. 120 The advantages to this feature have already been set forth. 125

Fig. 5 illustrates another modification in which the rotary pump 36 is driven by an electric motor (not shown) and in which 130

2 is the outlet from the pump 36 leading into the well for operating the jet pump A. The water from the jet pump flows up through the pipe 1 and divides into two 5 branches, one part passing through the pipe 49 to supply the pump 36 and the other part passing through the distributing pipe F. The distributing pipe has connected to it by the pipe 7 a distributing tank G, and 10 such pipe carries an inspirator 8. These parts correspond to similar parts as heretofore described in connection with Fig. 1 and the means for controlling the motor is the same. This construction is simpler than 15 that of Fig. 1 but is not adapted for high lifts since the upward velocity through the pipe 1 is depended upon to distribute the water. In the construction of Fig. 1 the water supplied to the low pressure pump 20 may be lifted to any desired height by such pump, while the high pressure pump supplies the pressure necessary to operate a jet at any depth, so that as compared with the construction of Fig. 5, the arrangement in 25 Fig. 1 is preferred because of the greater range of operation. To make this construction of Fig. 5 suitable for higher lifts, it would be necessary to place a distributing pump in the pipe F.

30 What I claim is:

1. In combination in a water distributing system for pumping water from a source of supply from which the water must be lifted, a rotary power pump comprising 35 a high pressure pumping element and a low pressure pumping element, a jet pump located in the source of water supply, a pipe for supplying water under pressure from the high pressure pumping element to the 40 jet pump, a pipe for supplying the water lifted by the jet pump to the inlet side of the low pressure pumping element, and connections from the outlet side of the low pressure pumping element for conducting a part 45 of the water to the inlet side of the high pressure pumping element and a part to other points for use.

2. In combination in a water distributing system for pumping water from a source 50 of supply from which the water must be lifted, a rotary power pump comprising a high pressure pumping element and a low pressure pumping element, a jet pump located in the source of water supply, a pipe for supplying water under pressure from the high pressure pumping element to the 55 jet pump, a pipe for supplying the water lifted by the jet pump to the inlet side of the low pressure pumping element, connections from the outlet side of the low pressure pumping element for conducting a part 60 of the water away for use and a part back to the inlet side of the high pressure pumping element, and a distributing tank positioned out of the line of flow and adapted

to carry air under pressure and connected to the outlet from the low pressure pumping element.

3. In combination in a water distributing system for pumping water from a source of supply from which the water must be lifted, 70 a jet pump located in said source of supply, rotary power pumping mechanism, connections whereby the water lifted by the jet pump is supplied to said pumping mechanism and whereby a part of the water from said pumping mechanism is supplied to operate the jet pump, a distributing outlet from said pumping mechanism, a distributing tank out of the line of flow through said 75 distributing outlet, and a single connection between said distributing outlet and the tank provided with an inspirator adapted to supply air to the tank.

4. In combination in a water distributing system for pumping water from a source of supply from which the water must be lifted, 80 a jet pump located in said source of supply, rotary power pumping mechanism, connections whereby the water lifted by the jet 85 pump is supplied to said pumping mechanism and whereby a part of the water from said pumping mechanism is supplied to operate the jet pump, a distributing outlet from said pumping mechanism, a distributing tank out of the line of flow through said 90 distributing outlet, a single connection between said distributing outlet and the tank provided with an inspirator adapted to supply air to the tank, and automatic means operated by the water in the tank, for turning on and off the power for said power pumping mechanism.

5. In combination in a water distributing system for pumping water from a source of supply from which the water must be lifted, 105 a jet pump located in said source of supply, a rotary power pumping mechanism, connections whereby the water lifted by the jet pump is supplied to said pumping mechanism and whereby a part of the water from 110 said pumping mechanism is supplied to operate the jet pump, a distributing outlet from said pumping mechanism, a distributing tank out of the line of flow through said distributing outlet, a single connection between said distributing outlet and the tank provided with an inspirator adapted to supply air to the tank, a float in the tank, 115 and means operated thereby for automatically turning on and off the power for said pumping mechanism.

6. In combination in a water distributing system for pumping water from a source of supply from which the water must be lifted, 120 a jet pump located in said source of supply, rotary power pumping mechanism, connections whereby the water lifted by the jet pump is supplied to said pumping mechanism and whereby a part of the water from 125

said pumping mechanism is supplied to operate the jet pump, a distributing outlet from said pumping mechanism, a distributing tank out of the line of flow through said distributing outlet, a single connection between said distributing outlet and the tank provided with an inspirator adapted to supply air to the tank, and automatic means governed by the flow of water through said distributing outlet for turning on and off the power for said power pumping mechanism.

7. In combination in a water distributing system for pumping water from a source of supply from which the water must be lifted, 15 a jet pump located in said source of supply, rotary power pumping mechanism, comprising a pair of rotary pumping members and an electric motor for operating said members, connections whereby the water lifted 20 by the jet pump is supplied to the first of said pumping members, and whereby a part of the water from said first pump is supplied to the inlet side of the second pumping member, a connection leading from 25 the second pumping member for operating the jet pump, a distributing line from the first pumping member, an air pressure chamber for said line placed out of the line of flow, a single connection 30 between said distributing line and the air pressure chamber and a switch and connections associated with said chamber and governed by the flow of water through the distributing outlet for operating the switch to 35 turn on or cut off the supply of current to the motor.

8. In combination in a water distributing system for pumping water from a source of supply from which the water must be lifted, 40 a jet pump located in said source of supply, rotary power pumping mechanism, comprising a pair of rotary pumping members and an electric motor for operating said members, connections whereby the water 45 lifted by the jet pump is supplied to the first of said pumping members, and whereby a part of the water from said first pump is supplied to the inlet side of the second pumping member, a connection leading from the 50 second pumping member for operating the jet pump, a distributing outlet from the first pump member, a distributing tank connected to the distributing outlet by a single connection and out of the line of flow there- 55 through, a switch in said tank, and means governed by the water in the tank for operating the said switch.

9. In a non-storage water distributing system, the combination of a water-conducting line having an inlet end and a distributing outlet; power pumping means associated with said inlet end; and controlling means for said line and pumping means comprising a tubular member positioned 60 intermediate said inlet end and said outlet 65

and formed of a size to receive a relatively small quantity of water only from said line, said member closed whereby to constitute an air pressure chamber and positioned out of the line of flow in said line, an air intake 70 for said member, and automatic means for controlling said power pumping means directly associated with said pressure chamber and constructed to be operated as the pressure increases or decreases in said tubular member.

10. In combination in a water distributing system for pumping water from a source of supply, a jet pump located in such source of supply, rotary power pumping mechanism, 80 a connection for supplying water from the pumping mechanism to operate the jet pump, a distributing pipe, connections whereby the water lifted by the jet pump is supplied to the pumping mechanism and to the distributing pipe, a distributing tank out of the line of flow of the distributing pipe, but connected thereto through a single connection, and automatic means for securing a body of air under 85 pressure in said tank.

11. In combination in a water distributing system for pumping water from a source of supply, a jet pump located in such source of supply, rotary power pumping mechanism, 90 a connection for supplying water from the pumping mechanism to operate the jet pump, a distributing pipe, connections whereby the water lifted by the jet pump is supplied to the pumping mechanism and to the distributing pipe, a distributing tank out of the line of flow of the distributing pipe, but connected thereto through a single connection, and an inspirator in the 95 connection between the distributing pipe and the tank adapted to supply air under pressure to the tank.

12. In combination in a water distributing system for pumping water from a source of supply, a jet pump located in such source of 100 supply, rotary power pumping mechanism, a connection for supplying water from the pumping mechanism to operate the jet pump, a distributing pipe, connections whereby the water lifted by the jet pump is 105 supplied to the pumping mechanism and to the distributing pipe, a distributing tank out of the line of flow of the distributing pipe, a single connection between the distributing pipe and the tank provided with 110 an inspirator adapted to supply air to the tank, and automatic means operated by the opening and closing of the outlet from the distributing pipe for turning on and off the power for said power pumping mechanism.

13. In a non-storage water distributing system, the combination of a water-conducting line having an inlet end and a distributing outlet; power pumping means associated with said inlet end; and control- 115 120 125 130

ling means for said line and pumping means comprising a tubular member positioned intermediate said inlet end and said outlet and formed of a size to receive a relatively small quantity of water only from said line, said member closed whereby to constitute an air pressure chamber and positioned out of the line of flow in said line, an air intake for said member, and automatic means

for controlling said power pumping means 10 directly associated with said pressure chamber and constructed to be operated as the pressure increases or decreases in said tubular member; the inlet end of said line having a connection with the intake of the said 15 power pumping means.

THOS. H. HOLLIS.
